Primary Examiner — T. Chase Nelson*Assistant Examiner* — Ania Aman(74) *Attorney, Agent, or Firm* — Slater & Michaelson(57) **CLAIM**

The ornamental design for a fire pit accessory, as shown and described.

DESCRIPTION

FIG. 1 is a perspective view of a fire pit accessory; FIG. 2 is a left side elevational view thereof; FIG. 3 is a right side elevational view thereof; FIG. 4 is a front elevational view thereof; FIG. 5 is a rear elevational view thereof; FIG. 6 is a top plan view thereof; and, FIG. 7 is a bottom plan view thereof. The broken lines shown in the drawing views are included for the purpose of showing environmental structure that forms no part of the claimed design.
